DESIGN FOR A TOWEL RACK

Martin J. Grady, Chicago, Ill.

Application July 24, 1948, Serial No. 147,750

Term of patent 14 years

(Cl. D33—16)

To all whom it may concern:

Be it known that I, Martin J. Grady, a citizen of the United States, residing at Chicago, in the county of Cook, State of Illinois, have invented a new, original, and ornamental Design for a Towel Rack or the like, of which the following is a specification, reference being had to the accompanying drawing, forming a part thereof, wherein—

The essential feature of my design resides in the provision of a central support having a bar provided with a rounded U-shaped bend intermediate its ends and located on the front of said support.

I claim:

The ornamental design for a towel rack or the like, substantially as shown and described.

MARTIN J. GRADY.
